UNITED STATES PATENT OFFICE

160,306

AUTOMOBILE HOOD ORNAMENT

Everett A. Dunning, Detroit, Mich.

Application March 18, 1950, Serial No. 8,609

Term of patent 7 years

(Cl. D14—18)

To all whom it may concern:

Be it known that I, Everett A. Dunning, a citizen of the United States, residing in the city of Detroit, county of Wayne, and State of Michigan, have invented a new, original, and ornamental Design for an Automobile Hood Ornament, of which the following is a specification, reference being had to the accompanying drawing, forming part thereof, in which:

Fig. 1 is a front elevational view of an automobile hood ornament showing my new design;

Fig. 2 is a top plan view thereof;

Fig. 3 is a side elevational view; and

Fig. 4 is a cross sectional view taken on the line 4—4 of Fig. 2.

The characteristic features of my design reside in the parts shown by means of full lines in the drawing.

I claim:

The ornamental design for an automobile hood ornament, substantially as shown and described.

EVERETT A. DUNNING.
